MULTIUNIT ELECTRON TUBE

William W. Eitel, Woodside, and Jack A. McCullough, Millbrae, Calif., assignors to Eitel-McCullough, Inc., San Bruno, Calif., a corporation of California

Application June 9, 1947, Serial No. 753,494

5 Claims. (Cl. 250—27.5)

1

Our invention relates to electron tubes of the power or transmitting tube type, and more particularly to improvements in multi-unit tubes of the character disclosed in our U. S. Letters Patents Nos. 2,424,683, 2,424,684, and 2,424,685.

The trend in electron tube design is toward tubes capable of operation at the higher frequencies. It is not difficult to achieve the desired electrical properties for good operation at high frequencies with tubes of small physical size because small tubes have certain inherent advantages from the standpoint of tube structure and geometry, such as maintaining closer electrode spacings and lower inductance leads. The disadvantage of small structures for power tube uses is the limitation on power output due to lack of heat dissipation from the electrodes, particularly from the anode. In other words, large physical size is incompatible with electrical properties required for higher frequency operation, and this would appear to put a ceiling on power output for high frequency tubes.

The broad object of our invention is to provide a tube capable of large power output without sacrifice of those electrical properties required for high frequency operation.

Another important object is to provide a tube structure which simplifies the manufacture of power tubes, and which enables a variety of tubes of different power ratings to be built, all from basic tube units made alike.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a side view, partly in section and partly in elevation, showing a tube embodying the improvements of our invention; and

Figure 2 is a top view of the same.

In terms of broad inclusion, our electron tube comprises a plurality of tube units rigidly connected together as a single structural body, each unit comprising an individual envelope having a portion forming an external anode, and a cooler structure carried by the anodes of the units comprising a set of fins on each of the anodes and a housing connecting the sets of fins. In our preferred tube the tube units are disposed in a circle and the housing of the cooler structure is circular and arranged coaxial with the circle of

2

tube units. The envelope of each tube unit preferably has coaxial connector members thereon to which electrodes in the envelope are connected, and terminals are provided externally of the units connected to such members.

In greater detail and referring to the drawings, we show four triode tube units 2 preferably arranged in a circle about a vertical axis, it being understood that a greater or less number of tube units may be employed and that the individual units may be other than triodes such as diodes or tetrodes. The tube units illustrated each comprise an anode 3, filamentary cathode 4 and control grid 6, these being each complete tube units independently constructed and evacuated.

Anodes 3 are of the external anode type adapted for cooling by forced air or the like, and are connected to a common cooler structure 7. This cooler structure is preferably circular in shape coaxial with the circle of tube units, and functions as an electrical terminal for the anodes as well as supporting connection for tying the tube units together.

A feature of our present invention is that the cooler structure comprises a set of fins 8 connected to each of the anodes, which sets of fins are connected together by a housing made up of apertured end plates 9 and a cylindrical wall 11. A center post 12 secured between the end plates 10 by screws 13 serves to fasten the cooler structure together. These parts may conveniently be of a light weight metal such as aluminum. Fins 8 in the four sets preferably extend longitudinally and radially of the respective anodes, each set of fins being connected to a tubular core piece 14 which in turn is secured to the anode by solder 16. A sleeve 17 is also preferably provided about each set of fins. By this arrangement a series of annular passages containing fins 40 are provided in the cooler structure through which air may be directed. The columns of air discharging out the bottom of the cooler structure are directed along the lower portions of the tube units and serve to ventilate these parts.

45 For purposes of appearance and protection the cooler core 14 is preferably a cup-shaped piece with a closed upper end 15. Another feature of our present invention relates to the coaxial arrangement of electrode 50 connectors on the individual envelopes and the electrode terminal connections thereto. As shown in Figure 1, anode 3 forms the upper portion of the envelope and comprises a metal cup with an exhaust tubulation 18 at the top and a sealing flange 19 at the bottom. Metallic tubu-

lation 18 is pinched off at tip 21 after evacuation of the envelope. Flange 19 is sealed to a cylindrically-shaped envelope section 22 of vitreous material such as glass. A grid connector ring 23 is sealed to the lower end of wall section 22, and a pair of concentric cathode connector members 24 and 26 are arranged coaxially of ring 23. By this construction the cathode connectors are disposed at the envelope end opposite the anode and the grid ring 23 lies between. The envelope is completed by a glass section 27 sealed between grid ring 23 and the tubular outer cathode connector 24, and by a glass ring 28 sealed between metal flanges 29 and 31 on the cathode connector members.

Internally of the envelope the cage-type control grid 6 is supported on its connector ring 23 by a conical bracket 32. The filamentary cathode illustrated is made of hairpins of thoriated tungsten wire secured at the lower ends to alternate tabs on flared supports 33 and 34 connected to tubular extensions 36 and 37 of the cathode connector members 24 and 26. These filaments are tensioned by a spring pressed sleeve 38 sliding on a center rod 39 and bearing against an upper spider 41 having radial arms engaging the bights of the filaments. This particular filament structure forms no part of our present invention, it being understood that any suitable type of cathode may be used.

Externally of the tube units the grids are connected together by a common terminal 42 which is preferably a metal plate or disk having apertures for receiving the grid rings 23. Suitable fastening means is provided between terminal disk 42 and the grid rings. A satisfactory means comprises arcuate lugs 43 arranged in pairs spaced about the periphery of the aperture and clamped together by screws 44. These lugs provide the necessary electrical connection and mechanical support. A pair of cathode terminal plates or disks 46 and 47 are likewise arranged below the grid terminal. Disk 46 has apertures for receiving the outer cathode connector members 24, and disk 47 has apertures for receiving the projecting inner cathode connector members 26. Suitable connector lugs 43 similar to those above described are used to clamp the parts together. It will be seen that the superimposed disks 42, 46 and 47 function to mechanically tie the lower portions of the tube units together as well as to provide terminals for corresponding electrodes. The units are thus rigidly connected at the top by the cooler structure and at the base by the terminal disks.

The improved terminal arrangement at the base is made possible by the coaxial arrangement of the grid and cathode connector members on the units, which coaxial alignment enables the terminal disks to be positioned with registering apertures one above the other during assembly of the tube. The aligned connector and apertured terminal disk arrangement also results in a very rigid interconnecting structure at the base ends of the units.

We claim:

1. A multi-unit electron tube comprising a plu-

rality of tube units disposed in a circle rigidly connected together as a single structural body, each unit comprising an individual envelope having a portion forming an external anode, and a cooler structure carried by the anodes of the units comprising a set of radial fins on each of the anodes extending longitudinally thereof, and a circular housing coaxial with said circle of units and connecting said sets of fins.

10 2. A multi-unit electron tube comprising a plurality of tube units rigidly connected together as a single structural body, each unit comprising an individual envelope having coaxial connector members thereon, electrodes in each unit connected to said members, and terminals externally of the units connected to said members.

20 3. A multi-unit electron tube comprising a plurality of tube units rigidly connected together as a single structural body, each unit comprising an individual envelope having an anode at one end, a cathode connector member at the other end and an intermediate grid connector ring coaxial with said member, a cathode in each unit connected to said member, a grid in each unit connected to its ring, a grid terminal externally of the units connected to said rings, and a cathode terminal externally of the units connected to said members.

40 4. A multi-unit electron tube comprising a plurality of tube units rigidly connected together as a single structural body, each unit comprising an individual envelope having an anode at one end, a pair of concentric cathode connector members at the other end and an intermediate grid connector ring coaxial with said members, a cathode in each unit connected to said pair of members, a grid in each unit connected to its ring, a grid terminal externally of the units connected to said rings, and a pair of cathode terminal members externally of the units connected to said pairs of members.

50 5. A multi-unit electron tube comprising a plurality of tube units rigidly connected together as a single structural body, each unit comprising an individual envelope having coaxial connector members thereon, electrodes in each unit connected to said members, and spaced terminal plates extending transversely of the tube units and having aligned apertures for receiving the connector members.
